UNITED STATES PATENT OFFICE.

WALTER D'A. RYAN, OF LYNN, MASSACHUSETTS, ASSIGNOR TO GENERAL ELECTRIC COMPANY, A CORPORATION OF NEW YORK.

ARC-LAMP.

946,156.

Specification of Letters Patent. Patented Jan. 11, 1910.

Application filed November 18, 1903. Serial No. 181,581.

To all whom it may concern:

Be it known that I, WALTER D'A. RYAN, a subject of the King of Great Britain, residing at Lynn, county of Essex, and State 5 of Massachusetts, have invented certain new and useful Improvements in Arc-Lamps, of which the following is a specification.

The object of my present invention is to improve the construction and operation of 10 arc lamps.

The particular type of lamp which I have hereinafter described and illustrated is a so-called "twin arc lamp", in which a pair of arcs in series are employed in the same 15 lamp structure, although all of the features of my invention are not limited to such a construction.

My invention in the form illustrated is characterized, in its more limited aspect, by 20 the following facts: The two arcs extend in opposite directions from a fixed electrode to movable electrodes, a suitable magnetic field being provided to correctly position the arcs; a single dash-pot is arranged to control the 25 combined motion of both movable electrodes or the motion of either one separately; suitable regulating means are employed for controlling each arc and the regulating means for each arc is more or less dependent upon 30 the condition of the other arc.

My invention also contemplates certain improvements in the electrodes and means for producing an even magnetic field, and other features of construction of the lamp.

35 All of the features of novelty possessed by my invention are pointed out in the claims annexed to and forming a part of this specification.

For a better understanding of my invention, reference may be had to the accompanying drawings, of which—

Figure 1 is an elevation partly in section illustrating the construction of a lamp embodying my invention; Fig. 1^a is a partial sectional plan view taken on the line A A of Fig. 1 showing the arrangement of the electrodes; Fig. 1^b is a similar view showing a modified arrangement of the electrodes; Fig. 2 is an elevation partly in section taken 45 at right angles to Fig. 1; Fig. 3 is a diagram illustrating one arrangement of the electrical circuits of my lamp; and Fig. 4

is a diagram illustrating a somewhat different arrangement of circuits.

Referring to the drawings, a hood 1 is shown from which the lamp mechanism is supported. A pair of posts 2 each secured at their upper ends to the hood 1 carry at their lower ends a platform 3. Posts 4 extending downwardly from the platform 3 carry at their lower ends another platform 5. Supports 6 and 7 are carried from the under side of the platform 3 and to these supports electrode-carrying members 8 and 9 are pivoted. The members 8 and 9 are each provided on their outer sides with a pair of solenoids or coils 10 and 11, and 12 and 13 respectively. The axes of these coils are substantially at right angles to the members 8 and 9. The armatures 14 and 15 of the coils consist each of a U-shaped bar of magnetic material held in position by members 16 and 17 respectively, which in turn are secured to opposite pairs of posts 4.

The members 8 and 9 carry at their lower 75 ends extensions 18 and 19 respectively, which extensions are pivoted to and insulated from the members 8 and 9 at the points 20 and 21 respectively. The extensions 18 and 19 pass through slots provided for the purpose in 80 the lower platform and have pivoted to them at their lower end clamping devices 22 and 23 respectively, in which the movable electrodes 24 and 25 respectively are secured. Binding posts 26 and 27 are carried by the 85 extensions 18 and 19 respectively, and flexible conductors not shown in the drawings secured to these binding posts form means for supplying current to the electrodes. The fixed electrode 28 shown in Fig. 2 is carried 90 in a support 29 connected to the lower platform by a pair of posts 30. The electrodes 24, 25 and 28 are in general similar to each other except that the electrodes 24 and 25 are only half as wide as the electrode 28. 95 As is clearly shown in Fig. 1^a the electrode 28 is located between the electrodes 24 and 25 which are so arranged that one is adjacent to one edge of the electrode 28 while the other is adjacent to the opposite edge of the 100 electrode 28. In the lamp illustrated, each electrode consists of a plate of carbon having kerfs or slots 31 formed in its lower end, thus dividing the arc end of each electrode

into a plurality of fingers or branches. As will be readily understood by those skilled in the art an arc will extend from but one finger of each electrode at a time. When the 5 finger from which the arc extends consumes away a certain amount the arc will shift to another finger on account of the decreased resistance of the second path. This separation of the electrode into fingers not only 10 localizes the arc but prevents the rapid conduction of heat from the crater and thus gives a more efficient illumination. By arranging the three electrodes in the manner shown the arcs formed between each movable 15 electrode and the fixed electrode are not co-axial. I find this desirable as otherwise there is a tendency for the two arcs to merge in one long arc which is objectionable. The lower platform also carries an electromagnet 20 33 for deflecting the arc between the ends of the electrodes. The core of the electromagnet is U-shaped and the legs of the U-shaped core extend through, and are secured to, the lower platform. The yoke of the U-shaped core, which is located above the platform, carries an exciting coil 34. The lower 25 end of each leg carries a flattened pole piece or shoe 35. In the form of my invention illustrated in the drawings the shoes are formed with threaded sockets into which the 30 ends of the legs of the core are screwed. By threading the shoes up or down on the legs of the core the position of the former may be altered with respect to the ends of the electrodes to vary the influence of the electromagnet on the arc. Suitable lock nuts 35' 35 may be employed to secure the shoes in any desired position. The pole pieces 35, which are placed at opposite edges of the fixed 40 electrode 28, have formed on their inner sides a number of substantially horizontal kerfs 36 thus dividing the pole faces into a plurality of fingers 37. This subdivision of the face of the pole piece of the electromagnet 45 insures a properly distributed magnetic field for directing the arcs between the electrode. By properly distributing the kerfs and proportioning the parts, the distribution of the magnetic field between the pole 50 pieces can be arranged as desired.

The members 8 and 9 are provided at their upper ends with the rigidly attached extensions 38 and 39. These extensions pass upward through apertures in the platform 55 or support 3 formed for the purpose. Links 42 and 43 are secured to the extensions 38 and 39 respectively at the points 40 and 41 respectively. The links 42 and 43 are pivoted to each other and to the movable member 46 of a dash-pot at the point 45. The other member 47 of the dash-pot is pivoted to a support 48 adjustably secured to the platform 3. By this arrangement a movement of either or both of the members 5 and 9 outward about their points of piv-

otal support tends to cause a separation of the members 46 and 47. The valves of the dash-pot are arranged to prevent a rapid movement of the member 46 in the upward direction.

Binding posts 48' and 49 carried by the upper platform 3 are connected to some suitable source of current supply. To avoid confusion, the various leads connecting the binding posts 48', 49 with the various solenoids and the electrodes of the lamp are not shown in Figs. 1 and 2 of the drawing. A suitable casing 50 depends from the lower edge of the hood 1 and carries at its lower edge a globe 51 which incloses the electrodes. 70 75 80

Referring to the diagram shown in Fig. 3, it will be seen that the binding post 48' and the electrode 24 are connected through windings 52, 53 and 54, these windings forming part of the windings of the coils 10, 11 and 34 respectively. Similarly the binding post 49 and the electrode 25 are connected through windings 52', 53', 54', which form part of the windings of the coils 12, 13 and 34 respectively. The binding post 49 and the stationary electrode 28 are connected by a circuit which includes the windings 55 and 56, these windings forming part of the windings of the solenoids 10 and 11. Similarly the binding post 48' and the stationary electrode 28 are connected by a circuit which includes windings 55' and 56', and these windings form part of the windings of the solenoids 12 and 13 respectively. The two parts of the windings of each of the coils 10, 11, 12 and 13 are arranged so that the passage of current through each of said parts tends to move the coil outward. 90 95 100 105 110 115 120 125 130

The operation of my lamp connected as shown in Fig. 3 is as follows: On the passage of current through the lamp, the members 8 and 9, which are normally held by gravity so that the electrodes 24 and 25 are in contact with the electrode 28, move outward by reason of the magnetic action between the coils 10 and 11, and 12 and 13, respectively, with the cores 14 and 15 respectively, until the magnetic forces pulling the members out are balanced by the weight of the members and parts carried thereby. 105 110 115 120 125 130 As seen in Figs. 1 and 2, suitable adjustable weights 8' and 9' are carried by the members 8 and 9 respectively by means of which the center of gravity of the members can be changed. Any sudden outward movement of either or both of the members is resisted by the action of the dash-pot. When the members 8 and 9 are moved outward, thereby moving the electrodes 24 and 25 away from the electrode 28, a pair of arcs is formed, one between the electrodes 24 and 28 and the other between the electrodes 28 and 25. Normally these arcs are substantial continuations of one another and are substantially of the same length. As the 130

electrodes begin to waste away or for any other reason the arc sprung between one set of electrodes, 28 and 25 for instance, becomes longer than that between the electrodes 24 and 28, the voltage of the two arcs becomes unequal, that between the electrodes 28 and 25 being the higher. This will cause more current to flow through the windings 55 and 56 in shunt to the arcs between the electrodes 28 and 25, and less current through the windings 55' and 56' which are in shunt with the arc between the electrodes 24 and 28. This variation of current in the shunt coils will cause a movement of the members 8 and 9 in the direction necessary to equalize the two arcs so that the arcs are automatically maintained in the same condition.

Preferably the electrodes 24 and 25 are inclined to the electrode 28, as shown in Fig. 1, as by this construction the tendency of the arc to creep up the electrodes against the action of the electromagnet 33 is lessened. By reason of the various pivotal connections between the electrodes 24 and 25 and the members 8 and 9 respectively, this angle can be maintained as the electrodes waste away.

In the diagram shown in Fig. 4 I have illustrated a somewhat different arrangement of circuits for my lamp. In this form of my invention the windings 52, 53, 54, 52', 53' and 54' are as shown in Fig. 3. The shunt coils 55 and 56' are in series with each other and in shunt to the arc between the electrodes 24 and 28, and the shunt coils 55' and 56 are in series with each other and in shunt to the arc between the electrodes 25 and 28. The windings 55 and 55' of this form of my invention are arranged to oppose the windings 52 and 52' respectively. The windings 56 and 56' are arranged, however, to assist the windings 53 and 53' respectively. With this arrangement, when the two arcs become unequal, that between the electrodes 24 and 28 being the longer, for instance, the increase of current in the coils 55 and 56' will tend to cause a movement of the electrode 24 toward the electrode 28 and a movement of the electrode 25 away from the electrode 28, thus evening the lengths of the two arcs. The corresponding decrease in the current flowing through the coils 55' and 56 will produce a corresponding decrease in the forces resisting this equalizing movement. Except, as noted, the operation of the lamps having the circuits shown in Figs. 3 and 4 is the same.

When the lamp is intended to be operated with direct current it is desirable that the positive movable electrode which, in Fig. 1^b, is assumed to be the electrode 24', should be about twice as thick as the negative movable electrode 25'. With this arrangement the middle electrode should be formed in two

parts 28' and 28'' which may or may not be integral with each other but may be carried in the same holder in any case. The part 28', which is adjacent to the electrode 25', is about equal in thickness to the electrode 24'; while the part 28'', adjacent to the electrode 24', is about equal in thickness to the electrode 25'. With this arrangement the consumption of all the electrodes will be substantially the same.

Instead of forming the windings 34 of the electromagnet 33 in two parts 54' and 54'', I sometimes dispense with one part, as for instance the part 54'.

While I have described and illustrated the best embodiments of my invention which are now known to me, yet it will be readily understood that many changes can be made in the form of my invention without departing from its spirit.

What I claim as new and desire to secure by Letters Patent of the United States, is,

1. In an arc lamp, a fixed electrode, a pair of separately movable electrodes arranged one on each side of the fixed electrode, and means for simultaneously moving said movable electrodes away from said fixed electrode and from each other to strike an arc between each of said movable electrodes and the fixed electrode.

2. In an arc lamp, a fixed electrode, a pair of separately movable electrodes arranged one on each side of the fixed electrode, and means for simultaneously moving said movable electrodes away from said fixed electrode to strike an arc between one of the movable electrodes and the fixed electrode, and a second arc in series with the first arc between the other movable electrode and the fixed electrode.

3. In an arc lamp, a pair of pivoted separately movable electrodes, a pivoted dash pot, and a pivotal connection between said electrodes and the dash pot.

4. In combination, a pair of pivotally-mounted electrodes, a pivoted dash-pot, and link connections between each of said electrodes and the dash-pot.

5. In an arc lamp, means for establishing and maintaining a pair of arcs in series with each other, said means comprising a pair of movable electrodes, means for moving said electrodes constructed and arranged so as to permit a movement of each electrode in the same and in the opposite sense from the corresponding movement of the other electrode, and a single dash-pot for regulating the movements of said electrodes.

6. In an arc lamp, a pair of separately movable electrodes, a fixed electrode, means for simultaneously moving said movable electrodes for establishing and maintaining two arcs in series, and a single dashpot for regulating the movement of each of said electrodes.

7. In an arc lamp, electrodes between which a pair of separate arcs are maintained, regulating means by which one arc may be shortened or lengthened when necessary independently of a similar change in length of the other arc, said means comprising electric devices responsive to changes in the condition of said other arc, and mechanical devices connecting the regulating means for each arc. 35
8. In an arc lamp, a pair of separately movable electrode-carrying members, a single dash-pot and a separate operating connection from each member to said dash-pot. 40
9. In an arc lamp, a pair of separately movable electrodes, a single regulating dash-pot, and separate operating connections from each of said electrodes to said dash-pot. 45
10. In an arc lamp, a fixed electrode, a pair of separately movable electrodes arranged one on each side of the fixed electrode, and means for moving said movable electrodes away from said fixed electrode and each other to strike an arc between each 50 of said movable electrodes and the fixed electrode and simultaneously maintaining such arcs. 55
11. In an arc lamp, a pair of electrodes, pivotally-mounted and separately movable supporting members therefor, and a dash-pot comprising two members, one of said
- members being pivoted to a fixed support, the other of said members being pivotally connected to each of the electrode-supporting members. 35
12. In an arc lamp, a fixed support, a pair of separately movable electrode-carrying members pivotally connected to said support, and a dash-pot comprising two members or parts, one of said parts being pivotally connected to said support, the other of said parts being pivotally connected to each of said electrode carrying members. 40
13. In an arc lamp, a fixed electrode, a pair of separately movable electrodes arranged one on each side of the fixed electrode, and means for simultaneously moving said movable electrodes toward and away from the fixed electrode and each other. 45
14. In an arc lamp, three electrodes, means for simultaneously maintaining arcs between one of said electrodes and each of the other two, the arc faces of each of said electrodes being divided by kerfs into a series of fingers or projections. 50

In witness whereof, I have hereunto set my hand this fourteenth day of November, 1903.

WALTER D'A. RYAN.
